UNITED STATES PATENT OFFICE.

ROSS CLARK BEEKMAN, OF KANSAS CITY, KANSAS.

WASHING MACHINE.

Application filed June 1, 1925. Serial No. 34,148.

My invention relates to improvements in washing machines and one object is to provide a machine which operates on the vacuum principle in forcing water through the articles to be cleansed, and possesses a plurality of relatively small cones or cups, forming a cone bed of relatively large area which operates over the greater portion of the bottom of the tub of the washer, instead of merely over a small portion thereof, as is customary.

A further object is to provide means for raising and lowering the clothes in conjunction with the cone bed, to the end that the washing operation may be accomplished in a more thorough and expeditious manner.

Another object is to provide a washing machine having a plurality of ducts arranged at the sides of and communicating with the interior of the tub, so that water or washing fluid may circulate through said ducts and the garments or articles being washed.

A further object is to provide a machine which can be operated manually or by power, such as an electric motor, or the like, and which can be quickly changed from the power type of machine to one operated by hand in case of accident to the power mechanism.

Other objects will hereinafter appear, and in order that the invention may be fully understood, reference will now be had to the accompanying drawings, in which:

Fig. 1 is a vertical central section of the machine.

Fig. 2 is a side elevation thereof with the lower portion of the legs broken off and the plunger shown by dotted lines raised from the tub.

Fig. 3 is an end elevation of the machine.

Fig. 4 is an irregular vertical cross section on line IV—IV of Fig. 2.

Fig. 5 is an irregular horizontal section on line V—V of Fig. 1, with the power mechanism removed and showing the top of the cone bed and the water channels or ducts formed at the sides of the tub.

Fig. 6 is a detail inverted plan view of the cone bed of the plunger.

Fig. 7 is a detail sectional view of certain gearing employed in driving the washing machine, or a wringer mounted thereon.

In carrying out the invention, I employ a frame consisting of legs 2, and a rectangu-

lar upper portion 5 in which a tub 6 is fixedly mounted. Said tub 6 has a lid 9 secured by hinges 11 to the rectangular portion 4 of the frame, and one or more bolts 12 to secure said lid in closed position. The tub 6 may be emptied of the washing fluid by a suitable drain cock 13. The legs 2 are braced at their intermediate portions with longitudinal and transverse tie rods 14 and 16, respectively. The lid 9, has apertures 15 to allow air to freely enter and escape from the tub 6 during the operation of the plunger hereinafter described in detail.

The four sides of the tub 6 are provided with exterior upwardly tapered water channels or ducts 17 communicating with the interior of said tub through a plurality of ports 18 and 19 near its upper and lower portions, respectively.

The washing operation is performed by a plunger 20 embodying a cone bed consisting of a plurality of inverted cups or truncated cones 22, secured to a plurality of cross members 24, fixed to a hollow rectangular sheet metal frame 26 provided with a wire screen top 28. The sides of the frame 26 have a plurality of openings 30, which, together with the screen 28, allow free circulation of the washing fluid. The cone bed is reinforced by longitudinal rods 36 and transverse rods 38 which latter extend through the lower margins of the cones 22. Said rods 36 and 38 constitute important features of the invention, as in practice garments or other articles to be washed, are hung or strung over said rods and thereby receive a vertical reciprocatory motion with the cone bed in its travel through the washing fluid, thereby greatly facilitating the washing process. Said rods 36 and 38 also serve to lift the clothes from the tub when the cone bed or plunger is raised to inoperative position, as shown by dotted lines, Fig. 2, thus allowing the surplus water to drain from the clothes or other articles before they are fed into the wringer.

The plunger 20 has a horizontally disposed arm 40 fixed to the cross members 24 and provided at its central portion with a vertical stem 42 reciprocably mounted in a tubular guide 44, fixed to the tub lid 9. The plunger 20 is actuated by mechanism embodying a pair of links 48, a lever 50, a connecting rod 52, a crank shaft 54, a bevel gear 56, a bevel gear 58 intermeshing with 110

said gear 56 and fixedly mounted upon a counter shaft 60, a worm wheel 62 fixedly mounted upon said counter shaft 60, a worm 64 intermeshing with said worm wheel 62, 5 a drive shaft 66 upon which said worm 64 is fixedly mounted, and a motor 68 for driving said shaft 66 and mounted upon a shelf 70 at one end of the washing machine.

The lever 50 has a fulcrum 72 mounted 10 in standards 74 fixed upon the lid 9. A counterweight 76 is fixed to the lever 50 on the opposite side of the fulcrum 72 from the links 48 to assist in carrying the weight of the plunger 20, so that less power will be 15 required to raise the latter. The connecting rod 52 is made in two sections 77 and 78 connected by a pivot 79 and a slideable sleeve 80, so that said connecting rod 52 may be broken or folded to allow the plunger 20 20 to be lifted out of the tub 6, as indicated by dotted lines Fig. 2, so that articles can be readily placed within or removed from said tub 6.

The bevel gear 56 is loosely mounted upon 25 one end of the crank shaft 54 and has a clutch member 82 for engagement with a clutch member 84 loosely mounted upon the adjacent ends of said crank shaft 54 and a counter-shaft 85, which latter is provided 30 with a loosely mounted bevel gear 86, which, like the bevel gear 56, is constantly in mesh with the bevel gear 58. The clutch member 84 has internal grooves 88 and 90 at its opposite ends to alternately receive 35 feathers 92 and 94 on the shafts 54 and 85, respectively. A lever 96 is pivotally connected to the clutch member 84 for the purpose of shifting the same into engagement with the feathers 92 to drive the shaft 54, 40 or into engagement with the feathers 94 to drive the shaft 85. The shaft 85 is provided with a fixedly mounted bevel gear 98, which intermeshes with a bevel gear 100 mounted upon one end of a shaft 102 provided 45 at its opposite end with a fixedly mounted bevel gear 104 intermeshing with a bevel gear 106 mounted upon a vertical shaft 108 adapted to drive a wringer, not shown, which may be mounted upon a cross bar 110 50 fixed to a trough 111 secured to one end of the frame 4 and the tub 6 and adapted to drain into the latter the washing fluid wrung from the clothes.

112 designates a removable false bottom 55 resting on the permanent bottom 114 of the tub 6 and adapted to hold the articles being washed a slight distance above said permanent bottom 114 to allow the washing fluid to circulate through said articles to the 60 best advantage, and also to hold the latter above the tub bottom 114 where the refuse collects as it is washed from the articles. Said false bottom 112 consists of a rectangular frame 116 covered with a wire screen 65 118. Slots 120 are provided in the sides

and ends of said frame 116 to allow the water to circulate therethrough and enter the openings 19 that communicate with the lower ends of the ducts 17.

140 designates a gas or other suitable burner supported beneath the bottom of the tub 6 by straps 142 secured to the rods 14. The nipple 144 of said burner is adapted to have a gas-hose or pipe, not shown, connected thereto so that a flame may be kept 70 under the tub 6 to heat the water therein. 75

When it is desired to place the garments or other articles in the tub 6, the lid 9 and the plunger 20 are raised to the dotted line position disclosed by Fig. 2. A number of 80 the articles may then be placed upon the false bottom 112 while other articles are hung or strung from the rods 36 and 38. The tub 6 is supplied with a suitable quantity of washing fluid which is heated and maintained 85 at the desired temperature by the burner 140. The plunger 20 is then lowered into the tub 6 and the lid 9 is closed and secured by the bolt 12. The motor 16 is then 90 started, and through the intervening mechanism hereinbefore described, moves the plunger 20 up and down. As the plunger 20 makes a downward stroke the cones 22 force a quantity of water through the articles, while a quantity of the water is forced out of the lower portion of the tub 6 through the slots 120 and the ports 19, and passes upwardly through the ducts 17, 95 from which it returns to the upper portion of the tub 6 through the ports 18. As the water returns to the upper portion of the tub it falls upon the articles being washed and thereby materially assists in cleansing the same. The reciprocatory motion of the 100 plunger 20 carries the clothes and other articles attached thereto up and down through the water and thus produces an action on the articles similar to that of rubbing them on a wash board.

On completion of the washing operation 110 the lid 9 is thrown back to the dotted line position shown by Fig. 2, lifting the plunger 20 therewith which carries the clothes attached thereto out of the water so that the attendant need not place her hands in the hot water or employ a stick for lifting the 115 articles from the tub.

In the event the motor 68 or the gearing 120 which it operates should get out of order, the connecting-rod may be disconnected from the lever 50 by removing the pivot 79, after which the lever 50 may be operated by hand.

From the foregoing description, taken in connection with the drawings, it is apparent 125 that I have provided a washing machine embodying the advantages above pointed out, and while I have shown and described the preferred construction, combination and arrangement of parts I re- 130

serve the right to make such changes as properly fall within the spirit and scope of the invention as claimed.

Having thus described my invention, what I claim and desire to secure by Letters Patent, is:

1. A washing machine consisting of a tub, a lid thereto, a reciprocatory plunger guided by said lid, a lever mounted upon the lid and operably connected to said plunger, a power driven shaft, a foldable connecting rod consisting of two sections hinged together and one of which is operably connected to said shaft and the other to the lever, and a sleeve 15 for engaging over said sections to secure the lever from accidentally folding.

2. A washing machine consisting of a tub, a lid thereto provided with slots, a reciprocatory plunger arranged within said tub 20 and embodying a stem, a tubular guide for said stem secured to the lid, a lever operably mounted upon the lid, links extending through the slots in the lid and pivotally connected to the plunger and said lever, and counterbalance means on said lever.

25 3. A washing machine consisting of a tub, a lid thereto provided with slots, a reciprocatory plunger arranged within said tub

and having a guide stem projecting through said lid, links extending through the slots 30 in the lid and connected to said plunger, a lever connected to said links, a crank shaft, a connecting rod operably connected to said crank shaft and the lever, and a motor geared to the crank shaft to drive the same. 35

4. A washing machine consisting of a tub, a lid hinged to said tub and provided with slots, a reciprocatory plunger arranged within said tub, a guide stem on said plunger extending through the lid, links connected 40 to the plunger and extending through the slots in the lid, and means for reciprocating said links.

5. In a washing machine, a plunger consisting of a hollow frame, cross members 45 spaced apart and secured to the upper portion of said frame, a screen secured to the upper portions of said frame and cross members, a plurality of inverted cups depending from each cross member, rods extending through spaces between said cups and secured to the ends of said frame, and other rods extending through the cups and crossing the first-mentioned rods. 50

In testimony whereof I affix my signature.
ROSS CLARK BEEKMAN.
